UNITED STATES PATENT OFFICE.

CHARLES E. GODLEY, OF YPSILANTI, MICHIGAN, ASSIGNOR TO EDMUNDS & JONES CORPORATION, OF DETROIT, MICHIGAN, A CORPORATION OF NEW YORK.

FOCUSING LAMP.

Application filed October 9, 1926. Serial No. 140,610.

My invention relates to focusing mechanisms for adjusting the position of a lamp bulb both longitudinally of a reflector and along one medial plane of the reflector. In general, my invention aims to provide a simple and easily assembled mechanism for this purpose and one in which an inexperienced user will not easily be confused as to the parts which are to be actuated for effecting each of these two adjustments.

More particularly, my invention provides a focusing mechanism which can easily be adapted to lamps having different spacings between the reflector and the back of the lamp casing, and one in which the entire mechanism can be mounted either on the reflector or on the back of the lamp casing. It also provides a mechanism for this purpose in which the means for actuating one of the adjustments are concentric with and mounted on the means for actuating the other adjustment, and aims to latch one of these actuating means against accidental movement during the actuating of the other adjustment.

More particularly, my invention provides a focusing mechanism in which a longitudinal adjustment of the lamp bulb is effected by sliding the lamp socket in the bore of the reflector, in which the vertical adjustment is effected by rocking the guide upon the wall of this perforation in the reflector, and in which the rocking of the socket is effected through a cam member pivoted on the screw which effects the sliding of the socket. It also provides simple and effective means for affording a non-rattling connection between certain parts of the mechanism and for permitting the guide to rock without tilting or cramping the screw employed for sliding the socket longitudinally.

Still further and also more detailed objects will appear from the following specification and from the accompanying drawings, in which

Fig. 1 is a fragmentary central, vertical and longitudinal section through an automobile headlight embodying my invention.

Fig. 2 is a plan view of the mechanism of Fig. 1, together with the rear end portion of the reflector of the headlight.

Fig. 3 is an enlarged front elevation of the cam disk of Figs. 1 and 2.

Fig. 4 is a similarly enlarged rear ele-

vation of the bight of the yoke which supports most of the focusing mechanism.

Fig. 5 is an enlarged perspective view of the cam-engaging member which effects the rocking of the socket.

Fig. 6 is an enlarged front elevation of the rear end portion of the reflector and of the shell of the socket, namely a view taken from the line 6-6 of Fig. 1 with the lamp bulb and the structure within the socket shell omitted.

Fig. 7 is a section similar to Fig. 1, showing another embodiment of my invention.

Fig. 8 is a vertical section taken along the line 8-8 of Fig. 7.

Fig. 9 is a bottom view of the focusing mechanism and rear reflector portion of Fig. 7.

Fig. 10 is a section similar to a portion of Fig. 7, but showing the longitudinal adjustment screw as swiveled on a bracket carried by the lamp casing.

Fig. 11 is a rear view of the central portion of the reflector.

Referring first to Figs. 7 to 10 inclusive, these show parts of an automobile headlight including a reflector 1 which has its rear end formed into a rearwardly extending cup 2. The rear end or bottom of this cup has a perforation 3 corresponding in horizontal diameter to the outside diameter of the shell 4 of a lamp socket, and this perforation has upper and lower enlargements to afford room for a bracket arm 5 and a tilting arm 6 which are secured respectively to the top and to the bottom of the socket shell. The upper bracket arm 5 carries at its rear end a fork which has parallel tines 7 extending downwardly at opposite sides of the axis of the reflector. These tines extend through the groove of a nut 8 and respectively engage opposite vertical walls of the bottom of the groove, the depth of the fork being such that the nut can slide somewhat vertically with respect to it, and the end walls of the groove being formed to permit a slight rocking of the nut upon the fork about an axis transverse of the axis of the reflector.

The back 9 of the casing of the headlight is provided with a perforation and the portion of the back adjacent to this perforation is formed into a guide tube 10 coaxial with the reflector. Freely rotatable in this guide

tube is the cup-shaped head 11 of a cam member which also includes a disk 12 provided with a spiral slot 13, this slot being involute with respect to a perforation 23 provided in the disk 12 coaxial with the head 11. Extending through the perforation 23 is a screw 14 which has its head 14^a disposed within the said cup-shaped head and which screw is threaded through the 10 nut 8.

The screw 14 also extends through and is journaled in the bight 15 of a rigid yoke which has arms 16 extending forwardly and these arms are secured to the opposite sides 15 of the cup formation 2 on the reflector. The bight 15 of the yoke bears rearwardly against the disk 12 and the screw 14 is prevented from moving longitudinally with respect to the said disk and the said bight 20 by suitable means, as for example by a spring washer 16^a which is interposed between the said bight and a pin 17 extending transversely through the shank of the screw, the location of the said pin being 25 such that the spring washer also draws the head 14^a of the screw against the rear face of the disk 12.

The lower or tilting arm 6 which is secured to the bottom of the socket shell 4 extends rearwardly through the spiral slot 13 of the disk and is preferably of a thickness closely approximating the width of that slot.

With the mechanism thus arranged, the 35 bight of the yoke (which yoke is fast on the reflector) has the screw effectively swiveled on it, so that the screw 14 cannot move longitudinally. When this screw is rotated in either direction, it moves the nut 8 longitudinally of the common axis of the screw and reflector, and the bracket 5 transmits this movement to the socket, thereby sliding the socket in the reflector perforation 3 to 40 adjust the lamp bulb 18 longitudinally of the reflector.

For the vertical adjustment, the cam member is rotated so as to vary the distance from the axis of the screw 14 (on which the same member is journaled) to the portion 50 of the spiral slot through which the tilting arm 6 extends, this slot being arranged after the manner shown in Fig. 3. By doing this, I cause the rear end of the rigid tilting arm 6 to be raised or lowered according to the 55 direction in which the slotted disk was rotated, thereby rocking the socket shell about the bore of the perforation 3 so as to lower or raise the lamp bulb.

To facilitate the independent manipulating of the two adjustments, I preferably 60 make the cup-shaped head 11 considerably greater in interior depth than the height of the head 14^a of the adjusting screw and I provide this head 11 with slot portions 20 65 which can be engaged either by a large sized

screw driver or by a coin 21 without having such an operating tool contact with the screw-head 14^a.

In the embodiment above described, the yoke can readily be of such rigidity as to support the entire focusing mechanism independent of the back of the lamp casing, or the head 11 may closely approach the bore of the tubular casing part 10 so as to be journaled in the latter, thereby making the 75 casing cooperate in the supporting. Or, I may support the mechanism entirely from the casing, as for example by employing a bracket 25 riveted to the back 9 of the casing and serving as a substitute for the yoke 80 of Figs. 7 and 9, after the manner shown in Fig. 10.

So also, other features of the heretofore described mechanism may be varied considerably. In practice, I preferably make the 85 tilting arm integral with the bracket arm which engages the nut, and for that purpose may employ a single-piece member formed as shown in Figs. 1 and 5. This comprises a forward arm 26 soldered to the bottom of 90 the socket shell 4, a riser portion 27 extending upwardly from the rear end of the arm 26 and having a perforation 28 through which wires 29 lead into the socket, an upper and substantially horizontal portion 30 95 disposed considerably above the axis of the socket, a nut-engaging portion 31 (which forms the thrust-transmitting portion of this single-piece member) and a lower or tilt-effecting rear arm 32. In this case, the portion 31 is desirably curved about a horizontal axis intercepting the axis of the 100 socket approximately opposite the perforated reflector tube end, while the nut 33 is a correspondingly curved punching provided with ears 34 which overhang opposite vertical edges of the portion 31 to hold the nut 105 against rotation.

Instead of using a cross-pin through the screw shank and a spring washer for effecting the swiveling of the screw after the manner of Fig. 7, I preferably interpose a compression spring 35 between the bight 15 of the yoke and the said portion 31, so that the spring also takes up any looseness in the 110 threading of the nut on the screw and serves as a friction-producing means to deter a rotating of the screw. Then I also provide the adjacent faces of the bight 15 and of the slotted disk with interengaging teeth (36, 115 37) to hold the disk against accidental rotation, these teeth being normally held in interengagement by the pressure of the 120 spring 35.

To adapt my focusing mechanism to lamps 125 having widely varying spacings between the back of the casing and the rear end of the reflector, I may form the larger actuating head 38 separately from the slotted disk 39 and may connect these elements by strips 130

40 secured to both, as shown in Figs. 1 and 2. In that case, I provide the shank of the screw 41 with a radial collar 42 bearing against the rear face of the slotted disk 39 and spaced from the slotted head 43 of the screw, so that I can suit various lengths of lamp casings by merely changing the lengths of the strips 40 and the lengths of the screw shank portion between the head 43 and the collar 42. However, it will be noted that the head 38, the strips 40 and the slotted disk 39 form a rigid unit which is the cam member of the focusing device of Figs. 1 and 2, as an equivalent of the single-piece cam member of Figs. 7, 9 and 10.

To allow for the rocking of the socket (and hence of the single-piece member illustrated in Fig. 5) without cramping the screw, I preferably elongate the perforation 44 vertically, this being the perforation through which the screw 41 extends. In making this member of thin material, I may provide its rear arm 32 with a stiffening ridge 45 as shown in Fig. 5.

25 To prevent the socket from rocking laterally, I preferably elongate the tubular formation 2 on the reflector vertically and make the width of the bore of this formation equal to the outside diameter of the socket shell. 30 4. By thus elongating it, I can provide a pair of parallel vertical guide walls engaging opposite sides of the socket shell as shown in Fig. 6.

35 However, I do not wish to be limited to these or other details of the construction and arrangement above described, as many modifications may obviously be made without departing either from the spirit of my invention or from the appended claims.

40 I claim as my invention:

1. In a lamp, a reflector having a substantially axial perforation, a lamp socket extending slidably through the perforation and adapted to rock in one plane about the wall of the perforation, a supporting member fast on the reflector, a screw effectively swiveled upon the supporting member and threadedly connected to the socket to adjust the socket axially, a cam member rotatably mounted on the screw, a tilt-effecting member fast on the socket and in operative engagement with the cam portion of the cam member, and means to rotate the cam member to tilt the socket.

55 2. A lamp construction as per claim 1, in which the cam member comprises a disk having a spiral slot housing a portion of the tilt-effecting member.

60 3. A lamp construction as per claim 1, in which the cam member includes a tubular portion housing the head of the screw and extending rearwardly beyond the head of the screw.

65 4. A lamp construction as per claim 1, in which the cam member includes a tubular

portion housing the head of the screw and extending rearwardly beyond the head of the screw, in combination with a casing housing the reflector and having its back provided with a perforation into which the 70 tubular portion of the cam member extends.

5. A lamp construction as per claim 1, in which the cam member and the supporting member are provided with interengaging formations for deterring rotation of the cam member, and spring means tending to hold the said interengaging formations interlocked.

6. In a lamp, a reflector having a substantially axial perforation, a socket extending 80 slidably through the perforation and adapted to rock on the wall of the perforation, a supporting member secured to the reflector and having a thrust receiving portion extending across the axis of the reflector, an adjusting screw extending through and swiveled upon the said thrust receiving portion, a cam member swiveled upon the adjusting screw and including a tubular head 85 slidably housing the head of the said screw, the said member also having a spiral slot, a tilt-effecting member fast upon the socket and in operative engagement with the said slot, whereby a rotation of the cam member 90 rocks the socket on the perforation wall, and a threaded connection between the socket and the adjusting screw whereby rotation of the screw slides the socket longitudinally with respect to the reflector.

7. A lamp including a reflector having a substantially axial perforation and a casing having its back definitely spaced rearwardly from the reflector, a screw supporting member mounted within the casing, a lamp socket extending slidably through the perforation and adapted to rock in one plane about the wall of the perforation, a screw effectively swiveled upon the supporting member, means affording a threaded connection between the screw and the socket whereby rotation of the screw slides the socket with respect to the reflector, a cam member rotatably mounted upon the screw and including a tubular head housing the head of the screw, and tilt-effecting means operatively interposed between the socket and the cam member whereby rotation of the cam member 100 rocks the socket about the said perforation wall, the depth of the cup-shaped head and the disposition of the screw-head being such as to keep the screw-head normally out of reach of a screwdriver tip spanning the said mouth and engaging the slot of the cup-shaped head.

8. A lamp including a reflector having a substantially axial perforation and a casing having its back definitely spaced rearwardly from the reflector, a screw supporting member within the casing, a lamp socket extending 110 115 120 125 130 slidably through the perforation and

- adapted to rock in one plane about the wall of the perforation, a screw effectively swiveled upon the supporting member, means affording a threaded connection between the screw and the socket whereby rotation of the screw slides the socket with respect to the reflector, a cam member rotatably mounted upon the screw, and tilt-effecting means operatively interposed between the socket and the cam member whereby rotation of the cam member rocks the socket about the said perforation wall.
9. In a lamp, a reflector having a substantially axial perforation; a yoke having its arms secured to the reflector and its bight spaced rearwardly from the reflector; a disk engaging the rear face of the bight and having a spiral slot, the disk and bight having aligned perforations; a screw extending through the said perforations; a lamp socket extending slidably through the perforation in the reflector and adapted to rock in one plane on the wall of that perforation; thrust transmitting means rigidly connected to the socket and threaded upon the screw and arranged to permit a rocking of the socket, an actuating element extending rearwardly beyond the head of the screw and fast upon the disk, and a tilt-effecting element fast with respect to the socket and extending through the said slot.
10. A lamp construction as per claim 9, in which the thrust-transmitting means include a nut bearing against the tilt-effecting element and interlocked with the latter to prevent rotation of the nut.
11. A lamp construction as per claim 9, in which the disk and the said bight are provided with interengaging formations for deterring rotation of the disk; in combination with spring means for pressing the disk against the bight to hold the said interengaging formations interlocked.
12. A lamp construction as per claim 9, in which the thrust-transmitting means include a nut bearing against the tilt-effecting element and interlocked with the latter to

prevent rotation of the nut, the nut being slidable on the said element in the said plane, and spring means for pressing the tilt-effecting element against the nut.

13. A lamp construction as per claim 9, in which the thrust-transmitting means include a nut bearing against the tilt-effecting element and interlocked with the latter to prevent rotation of the nut, the nut being slidab'e on the said element in the said plane, and spring means for pressing the tilt-effecting element against the nut; the bight and disk having interengaging formations for deterring rotation of the disk, and the spring means serving also to press the bight against the disk so as to hold the said interengaging formations interlocked.

14. In a lamp, a reflector having a substantially axial perforation; a yoke having its arms secured to the reflector and its bight spaced rearwardly from the reflector; a disk engaging the rear face of the bight and having a spiral slot, the disk and bight having aligned perforations; a screw extending through the said perforations; a lamp socket extending slidably through the perforation in the reflector and adapted to rock in one plane on the wall of that perforation; a tilt-effecting member fast upon the socket and having a portion extending through the said slot, the said member having an intermediate portion through which the screw extends; a nut slidable in the said plane on the said intermediate portion and threaded upon the screw; and means fast on the disk for rotating the latter.

15. A lamp construction as per claim 14, including a compression spring interposed between the said bight and the said intermediate portion, the screw having a part engaging the rear face of the disk and against which part the disk is pressed by the spring.

Signed at Detroit, Michigan, September 23rd, 1926.

CHARLES E. GODLEY.
